UNITED STATES PATENT OFFICE.

WILLARD PENNOCK, OF MINERVA, OHIO, ASSIGNOR TO THE CANTON STEEL FOUNDRY COMPANY, OF CANTON, OHIO, A CORPORATION OF OHIO.

METALLIC RAILWAY-TIE.

1,023,392.

Specification of Letters Patent.

Patented Apr. 16, 1912.

Application filed August 2, 1911. Serial No. 642,004.

To all whom it may concern:

Be it known that I, WILLARD PENNOCK, a citizen of the United States, residing at Minerva, in the county of Stark and State 5 of Ohio, have invented certain new and useful Improvements in Metallic Railway-Ties, of which the following is a specification.

This invention relates to improvements in metallic railway ties, and the objects of the present invention are, first, to provide a metallic railway tie of such a construction that the railway rails can be secured and held in true spaced relationship under all circumstances, and second, to provide means for securing the railway rail supports or bases together and securely tying the bases of each tie together in such a manner that they will not be disturbed as to their relative position during the time they are fastened together nor will they be disturbed as to their relative position by the removal of parts for any purpose and substituting new parts.

A further object of the present invention
25 is to provide means whereby the railway
rails will be held out of contact with the
metallic bases forming the supports for the
rails and a further object is to provide
means whereby the bases or more specifically
the rail supports are held in position to dis-
tinguish them from the bases of the
providing a stay or stay in place of the railway rail
is disclosed.

1050 5. *Starbahn* is numerically also the center frequency in milliseconds corresponding to a positive initial value of the process of the dichotomy in Fig. 5.

I did this accompanying you when you were present at the trial and you propose to prosecute with me for the death of this man, I am perfectly willing to do so.

supports or bases are provided for a single tie. These supports or bases are provided with the integral overlapping flanges 2 and the tie flanges 3, said flanges being located and arranged substantially as shown. For the purpose of providing means for holding cushion blocks between the supports or bases 1 and the bottoms of the railway rails said bases are provided with the side and end flanges 4 and 5, which flanges are preferably formed as best illustrated in Fig. 1. These flanges 4 and 5 provide sockets for the reception of the cushion blocks 6, which cushion blocks are preferably formed of wood and are for the purpose of providing the sufficient amount of elasticity between the metallic supports 1 and the railway rails. The side and end flanges 4 and 5, also provide means for holding the blocks 6 in proper position and prevent their displacement.

instead of lateral, there can be no lateral movement of the supports or bases during the time the keys are being driven into their normal position or while the same are being 5 removed for any purpose.

It will be understood that by providing the overlapping flange 2 the outer web of the railway rail will be seated under the bottom of said overlapping flange and by 10 providing the vertical portion 11, the outer face of the railway rail will come in contact with the inner face of the vertical flange 11, said vertical flange being formed of such a height that it will come quite close to the 15 bottom of the tread flange 12 of the railway rails.

For the purpose of holding the inner base flange of the railway rail the tie bar 7 is provided at its ends with the overlapping 20 tongues 13 and when the keys 11 are driven into their normal positions they will have a tendency to draw the tie bars 7 down and into the groove 14 between the integral flanges 3 and at the same time snugly seat 25 the overlapping tongues 13 upon the upper faces of the inner base flanges of the railway rails. In the drawings I have illustrated the keys 10 formed by bending pieces of metal in such a manner as to bring their 30 inner faces in close contact with each other, thereby providing means for spreading the non-connected ends of the wedges, after the wedges have been driven into their normal positions and into the position to hold the 35 tie bar 7 and the supports or bases 1 securely together.

It will be understood that by spreading the ends of the keys 10 there can be no displacement of said keys from any cause. For 40 the purpose of preventing any sliding movement of the supports or bases upon the road bed, said supports or bases are provided with the side and end flanges 15, which side and end flanges are designed to be inserted 45 in the road bed or foundation. For the purpose of providing means for supporting the bases 1 directly under the railway rails proper, the flanges 16 are provided, which flanges are preferably located at right angles 50 to the length of the railway rails proper as best illustrated in Fig. 3. These supporting flanges 16 also assist in preventing any creeping of the supports or bases 1, owing to the fact that they are located directly 55 under the railway rails. It will be understood that the side and end flanges 15 assist in preventing the creeping of the supports or bases 1. The supports or bases 1 are made up of what might be termed longitudinal 60 rectangular portions and lateral extensions, the lateral extensions are located at substantially right angles to the longitudinal portions and are so located for the purpose of more securely holding the bases 65 against displacement in directions lateral

to the length of the railway rails and at the same time better preventing the creeping of the supports or bases.

The flanges 3 upon each of the railway supports or bases should be spaced apart 70 a distance substantially equal to the thickness of the tie bars 7, or in other words the tie bars 7 should be formed of such a thickness that when they are placed in position they will fit closely between the inner faces 75 of the flanges 3, thereby providing substantially and comparatively rigid connection as between the flanges 3 and the tie bars 7, but the mechanical construction should be such that the tie bars can be easily connected but 80 at the same time connected in such a manner that little or no fitting of the parts is necessary when the ties proper are placed in position upon the railway bed.

Having fully described my invention what 85 I claim as new and desire to secure by Letters Patent, is—

1. In a metallic tie, the combination of railway rail supports, said supports provided with overhanging flanges, sockets 90 formed in the upper portions of the supports, flanges provided with elongated slots, tie bars located between the flanges provided with the elongated slots, said tie bars provided with elongated slots and tongues, 95 the tongues adapted to overlap the inner base flanges of the railway rail and a key adapted to connect the railway supports and tie bars together, substantially as and for the purpose specified. 100

2. In a metallic tie, the combination of railway rail supports, said supports provided with overhanging flanges, sockets formed in the upper portions of the supports, flanges provided with elongated slots, 105 tie bars located between the flanges provided with elongated slots, said tie bars provided with elongated slots and tongues, the tongues adapted to overlap the inner base flanges of the railway rail and a key adapted to connect the railway supports and tie bars together, and cushioned blocks adapted for contact with the bottom of the railway rails, substantially as and for the purpose specified. 110

3. In a railway tie of the class described, the combination of bases provided with end and side flanges adapted to be seated in a railway bed, socket flanges located upon the upper faces of the bases, cushioned blocks 115 adapted to be located in the sockets, flanges adapted to be seated upon the outer base flanges of the railway rails and means for tying the railway bases together, substantially as and for the purpose specified. 120

4. In a railway tie of the class described, bases provided with railway holding flanges, said bases provided with sockets formed in their upper faces, cushioned blocks located in the sockets, tie bar connecting flanges 125

- provided with vertical elongated slots, a tie bar provided with vertical elongated slots and tongues, the slots adapted to register with the vertical elongated slots formed in 5 the tie bar flanges upon the bases and keys adapted to hold the tongues of the tie bars in contact with the inner base flanges of the railway rails, substantially as and for the purpose specified.
- 10 5. In a railway tie of the class described, bases provided with railway holding flanges, said bases provided with sockets formed in their upper faces, cushioned blocks located in the sockets, tie bar connecting flanges provided with vertical elongated slots, a tie bar 15 provided with vertical elongated slots and tongues, the slots adapted to register with the vertical elongated slots formed in the tie bar flanges upon the bases and keys 20 adapted to hold the tongues of the tie bars in contact with the inner base flanges of the railway rails, and the keys adapted to be secured in fixed position, substantially as and for the purpose specified.
- 25 6. In a railway tie of the class described, railway rail supporting bases consisting of longitudinal and lateral portions located at substantially right angles to each other, sockets formed in the upper faces of the 30 bases, flanges extended inward and over the sockets for a portion of the width of the
- 35 sockets, tie bar connecting flanges and a tie bar and securing keys, the tie bar connecting flanges and the tie bar provided with vertical elongated slots and the keys adapted to draw the tie bar toward the bases, substantially as and for the purpose specified.
7. In a railway tie of the class described, the combination of railway bases, said railway bases provided with connecting flanges, 40 said connecting flanges provided with vertical elongated slots, a tie bar provided with vertical elongated slots and extended tongues and vertically tapered keys, substantially as and for the purpose specified. 45
8. In a railway tie of the class described, the combination of railway bases, said railway bases provided with connecting flanges, said connecting flanges provided with vertical elongated slots, a tie bar provided with vertical elongated slots and extended tongues and vertically tapered keys, and means for securing the keys in fixed position, substantially as and for the purpose specified. 50 55

In testimony that I claim the above, I have hereunto subscribed my name in the presence of two witnesses.

WILLARD PENNOCK.
